United States Patent Office.

RICHARD LEACH, OF LINWOOD STATION, PENNSYLVANIA.

Letters Patent No. 73,818, dated January 28, 1868.

IMPROVEMENT IN PICKER FOR LOOMS.

The Schedule referred to in these Letters Patent and making part of the same.

TO ALL WHOM IT MAY CONCERN:

Be it known that I, RICHARD LEACH, of Linwood Station, in the county of Delaware, and State of Pennsylvania, have invented a new and useful Improvement in Picker for Looms; and I do hereby declare that the following is a full, clear, and exact description thereof, which will enable those skilled in the art to make and use the same, reference being had to the accompanying drawings forming part of this specification, in which—

Figure 1 represents a side view of my improved picker.

Figure 2 is a cross-section, taken in the line $z z$, fig. 1.

Similar letters of reference indicate corresponding parts.

This invention relates to improvements in the construction of a picker for looms, and consists in arranging and securing strips of leather upon the staff in such manner that the picker shall operate on the shuttle with superior effect in driving it, and shall be very durable, while at the same time it is exceedingly cheap and easy of construction.

A is the staff, and B is a pad or cushion, formed of several strips of sole-leather, $\alpha \alpha$, laid side by side, and joined together with pegs, or by sewing, the strips $\alpha \alpha$ being placed edgewise against the staff, as shown in fig. 2. The pad B, thus formed and placed upon the staff, is bound and held in position by a leather band, C, which passes around it, and is fastened at the laps by a wire-staple clasp, b, which runs through the laps of the band C and the pad B, and has its ends clinched to fasten the band and pad firmly together. By this fastening with a wire-staple clasp, the shuttle is prevented from splitting the picker, and wearing in the leather beyond a certain distance. A screw, c, is inserted through the band C into the back of the picker-staff A, which holds the picker in place, and prevents it from slipping.

The picker can be made out of waste scraps of leather, so that it costs only a trifle, and it will wear for an indefinite length of time without repair or renewal.

Having described my invention, I claim as new, and desire to secure by Letters Patent—

The combination of the pad B, band C, staple-clasp b, and screw c, with the staff A, all constructed, arranged, and operating as described.
